UNITED STATES PATENT OFFICE.

LEO A. MATTES, OF BERKELEY, CALIFORNIA.

CLEANING AND DISINFECTING POWDER FOR THE REMOVAL OF STAINS, INCRUSTATIONS, &c.

1,118,209.

Specification of Letters Patent.

Patented Nov. 24, 1914.

No Drawing.

Application filed July 7, 1914. Serial No. 849,486.

To all whom it may concern:
Be it known that I, LEO A. MATTES, a citizen
of the United States, residing in Berkeley,
in the county of Alameda and the State
of California, have invented a new and use-
ful cleaning and disinfecting powder for
the removal of stains, incrustations, and
disagreeable odors found in many water-
closet bowls, of which the following is a
specification.

The incrustations and stains usually found
in water-closet bowls are due to certain cal-
cium, magnesium and iron salts deposited
from the water standing in the bowl from
time to time, and the urine after standing
a short time deposits some of its chemical
constituents as well.

The accumulation of these deposits re-
sults in the water-closet bowl becoming
very unsightly, unsanitary, and oftentimes
emitting a disagreeable odor, and the object
of my invention is to provide a convenient
means for removing these objectionable fea-
tures in an easy and safe manner. This
point is attained by the use of a dry pow-
der, resulting from a thorough mixture of
two to three parts of dry powdered sodium
pyrosulfate with one part of dry sodium
chlorid. This powder when sprinkled into
the bowl, in which there is water, and
allowed to stand for a few minutes, and by
slightly rubbing and flushing the bowl, will

leave the bowl in a clean and white condi-
tion. By the use of this powder I claim
vast improvement over the use of hydro-
chloric acid or other like acids, as the acids
are dangerous due to their strong caustic
action, and hydrochloric acid emits ob-
noxious fumes which are irritating to the
eyes and nostrils, and also due to its strong
caustic properties it is damaging to the ves-
sel on which it is used. Wherein by the use
of the powder the above objectionable fea-
tures are overcome. The sodium pyrosul-
fate in itself is a good solvent for most of
these deposits, but in conjunction with so-
dium chlorid and in the presence of water,
a chemical reaction takes place, in which
better results are obtained.

It is not my intention to limit the scope
of the invention to the particular propor-
tions of the ingredients set forth, as the
quantities may have to be modified to attain
the best results with varying conditions as
found.

I claim:

A cleaning and disinfecting powder re-
sulting from the mixture of sodium pyrosul-
fate and sodium chlorid, substantially as
described, and for the purpose specified.

LEO A. MATTES.
